US00D769264S

(12) **United States Design Patent** (10) **Patent No.:** **US D769,264 S**
Kisselev et al. (45) **Date of Patent:** **** Oct. 18, 2016**

(54) **DISPLAY SCREEN WITH GRAPHICAL USER INTERFACE**

(71) Applicant: **Microsoft Corporation**, Redmond, WA (US)

(72) Inventors: **Sergey Kisselev**, Woodinville, WA (US); **Andrew M. Pickard**, Seattle, WA (US)

(73) Assignee: **Microsoft Corporation**, Redmond, WA (US)

(**) Term: **15 Years**

(21) Appl. No.: **29/534,464**

(22) Filed: **Jul. 29, 2015**

(51) **LOC (10) Cl.** **14-04**

(52) **U.S. Cl.**

USPC **D14/485**

(57) **CLAIM**

The ornamental design for a display screen with graphical user interface, as shown and described.

DESCRIPTION

The sole FIGURE is a front view of a display screen with graphical user interface showing our new design.

The broken line showing of the display screen, text, and graphic features forms no part of the claimed design.

1 Claim, 1 Drawing Sheet
